UNITED STATES PATENT OFFICE.

CARL PESCHKE AND HERMAN KILLIAN, OF DETROIT, MICHIGAN.

SMOKEHOUSE.

Application filed October 20, 1924. Serial No. 744,745.

To all whom it may concern:

Be it known that we, CARL PESCHKE, a citizen of Germany, and HERMAN KILLIAN, a citizen of the United States, residing at 5 Detroit, in the county of Wayne and State of Michigan, have invented certain new and useful Improvements in Smokehouses, of which the following is a specification, reference being had therein to the accompanying 10 drawing.

This invention relates to the smoking or curing of sausages, fish, meat and other articles or substances which it may be desired to subject to the action of smoke or fumes 15 in order to effect the flavoring, preserving or obtaining of cured conditions in the said articles or substances, which is a practice very often bordering on an art and requiring care as to the nature, application and 20 duration of the treatment in order that the best results may be obtained.

This invention therefore has as its principal object to provide an apparatus constructed in a manner adapted to facilitate 25 the smoking of articles or substances such as those suggested in progressive stages of intensity as to treatment, whereby a thorough curing or permeation of the said articles or substances by the smoke is effected.

It is also an object of the said invention 30 to provide an apparatus adapted for the subjecting of travelling articles or substances to the action of smoke of increasing in intensity as the said articles or substances 35 progress in their travel; an incidental object being to provide a smoke chamber of substantial length through which the articles or substances are adapted to be passed and to which at various stages in the length 40 thereof volumes of smoke of respectively varied intensity are admitted, the intensity referred to being not merely or necessarily one of a volume, but of character such as density, mechanical structure or heat or of any 45 combination of such characteristics as may be desirable for the purposes sought and suitable to the nature of the articles or substances to be treated.

Still further objects subsidiary to or resulting 50 from the aforesaid objects, or from the construction or operation of the invention as it may be carried into effect, will be

come apparent as the said invention is hereinafter further disclosed.

In carrying the said invention into effect, 55 we may provide an apparatus wherein a smoke chamber of substantial length is mounted over a plurality of fire boxes or chambers arranged in a series therebeneath with their upper ends opening successively 60 into the base of said chamber and adapted to each house a burner or fire for the purpose of producing a suitable smoke therein so that the smoke issuing from each of the fire boxes may be of differing intensity in 65 each case, and means associated with the said smoke chamber for the conveying therethrough of articles or substances whereby they will pass progressively over the fire boxes and will be subjected during such passage to the different characters of smoke 70 issuing therefrom.

All of which is more particularly described and ascertained hereinafter, by way of example, having reference to the accompanying drawing, in which

Figure 1 is a vertical longitudinal section of an apparatus constructed in accordance with the said invention; and

Figure 2 is a fragmentary transverse section, taken on the line 2^x—2^x of Figure 1.

Similar characters of reference indicate similar parts in both figures of the drawing.

The said apparatus in this instance is indicated as being of a two-story construction, 85 1 being the curing floor, and 2 the firing floor, the curing floor supporting a smoke chamber 3 which is in the form of an elongated compartment having end doors 4 and 5. This compartment is also provided with end openings 6 and 7 through which passes an endless fan or conveyor 8 and rails 9 which are mounted upon brackets 10 extending inwardly from the side walls of the chamber 3. The said endless chain is 90 mounted upon sprockets 11 and 12, the former of which is adapted to be driven by a motor 13 mounted upon one end of the said chamber.

14 is a carriage, the wheels 15 of which 100 travel on the rails 9, the said carriage supporting a cage which comprises a framework 16 having transverse end rails 17 upon which rods 18 are mounted, these rods being

indicated in this case as providing a support for sausages 19, although it will be readily understood that the cage may be of any form suitable to the carrying of other articles or substances which it may be desired to introduce into the apparatus. The said cage is adapted by reason of the carriage to be passed through the said compartment 3 from end to end, its entrance and egress being permitted by the opening of the doors 4 and 5 as required, these doors being maintained closed, however, while the cage is passing through the said compartment in order to prevent unnecessary escape of smoke or fumes therefrom. To effect the movement of the cage through the said compartment, the chain 5 is provided with a plurality of hooks 20, either of which may be engaged with the carriage 14 to transmit motion thereto, and the number of cages which may be so moved at one time will be dependent upon the size of the apparatus and the number and relative spacing of the hooks on the said chain in a device constructed in this particular manner.

The success of the treatment of the articles or substances so passed through the smoke chamber depends to a very great extent upon the duration of the treatment, character of the smoke and the manner in which they are subjected to the smoke in the said smoke chamber, the first two of which conditions may be governed by the speed of travel of the cage through the smoke chamber and by the nature of the fire producing the smoke, and the last mentioned condition we obtain by the provision of means for the introducing into the chamber in stages throughout the length thereof of smoke of various intensities whereby the articles or substances carried by the said cage are successively subjected to smoke within the smoke chamber of such various intensities.

In the curing of sausages, for example, it has been found that superior results can be obtained by first mildly smoking them and then progressively increasing the intensity and heat of the smoke as the curing action takes place; and in the device illustrated this effect is simply and efficiently secured by the provision beneath the smoke chamber of upwardly opening fire boxes 21, 22 and 23 intended to house fires of a nature giving progressively increasing intensities of smoke which is admitted through gratings 24 to the said smoke chamber 3, whereby the smoke in the said chamber is substantially more intense near the egress end thereof, as also is the temperature where a hotter fire is provided in the fire box 23 than in the fire box 21, 25 being smoke stacks for the eventual escape of the smoke from the smoke chamber 3.

These smoke stacks may be so spaced and

arranged that they tend by the draft created thereby to prevent the intermingling of the smoke from the several fire boxes and thereby maintain the varied smoke atmosphere desired in the chamber.

Fire doors 26 may be provided accessible from the firing floor 2 to facilitate the building and cleaning out of fires in the said fire boxes.

The apparatus described is more particularly intended for the smoking of sausages, although it may be used for the smoking of any other article or substance in which it is desirable that variation in the intensity of the treatment throughout the operation be obtained, and the precise form of the construction and its operating parts may be varied to suit the capacity required or particular characteristics of the articles or substances to be treated as will be readily understood; and the nature of fire or fuel producing means will be also dependent upon the particular result sought for or the form of fuel available or desirable.

This invention may be developed within the scope of the following claims without departing from the essential features of the said invention, and it is desired that the specification and drawing be read as merely illustrative and not in a limiting sense, except as necessitated by the prior art.

What we claim is:—

1. Smoke house apparatus comprising, an elongated smoke chamber, a conveyor travelling the length thereof, and fire boxes arranged beneath said smoke chamber, said boxes being adapted to admit smoke to said chamber in stages throughout its length whereby smoke of varied densities may be provided in said chamber.

2. Apparatus according to claim 1, where in travelling means are provided for the supporting of articles in said smoke chamber, rails for the guidance of said means, and entrance and egress doors at opposite ends of said smoke chamber.

3. Apparatus according to claim 1, where in the fire boxes are arranged in a series beneath said smoke chamber, whereby a progressively varied intensity of smoke is admitted thereto throughout the length thereof.

4. Apparatus according to claim 1 of two-story construction, the smoke chamber occupying a floor and the fire boxes being arranged upon a floor therebeneath from which access to said fire boxes is gained.

5. In a device of the class described, an elongated smoke chamber, conveying means extending the length thereof, said smoke chamber having a series of openings in the base thereof in the direction of its length, and a separate fire box beneath each of said openings.

6. A device according to claim 5, wherein the smoke chamber is provided with smoke stacks arranged above said fire boxes.

7. A device according to claim 5, wherein the smoke chamber is provided with a series of smoke stacks creating an upward draft, and preventing the complete intermingling of smoke from the several fire boxes.

In testimony whereof we affix our signatures in presence of two witnesses. 10

CARL PESCHKE.
HERMAN KILLIAN.
